ABSTRACT: Method and apparatus for drawing sheet glass, wherein the temperature of the incipient sheet from the line of draw to the drawing rollers is controlled at and along the width of the sheet to effect uniformity of thickness of the sheet throughout its width. Control is effected by establishment of a plurality of series of individual compartments in contiguous side-by-side relation and extending along lines which are generally parallel with the sheet and extend transversely of its length direction, closely adjacent the line of draw. Each series of compartments is allochirally positioned on a respective side of the sheet or line of draw; and each compartment is individually supplied with coolant at an individually controlled rate. By such individual control of the rate of flow of coolant it is assured that the temperature of each section of the sheet, consisting of an increment of length thereof, extending transversely from one side edge of the sheet to the other, is uniform and the temperature differences between one such increment and the next adjacent one are maintained at proper predetermined values. Control of rate of circulation of coolant through the several compartments may be automatic.

**METHOD AND APPARATUS FOR DRAWING SHEET
GLASS**

This invention relates to the fabrication of sheets of thermoplastic materials by drawing and, in particular is concerned with the production of glass in sheet form by vertical drawing from a bath of molten glass.

In this fabrication the molten glass as it is drawn from the bath by the machine, is rapidly cooled by heat exchange means disposed at each side of the incipient ribbon. Such cooling is necessary in order to bring the glass to a physical state such that it may be gripped without damage, between the rolls of the drawing apparatus. During its passage through the drawing shaft or chamber the glass is annealed by gradually lowering its temperature at a controlled rate. This annealing is necessary in order to avoid the development of excessive internal stresses within the glass.

Control and regulation of temperature and rate of cooling is necessary at every stage of production, in order to obtain properly annealed sheets of good quality and uniform desired thickness.

Defects due to variations in thickness of the sheet are caused largely by variations in temperature of the glass at the moment of formation of the ribbon, that is, at the location where molten glass at the foot of the ribbon, curves upwardly with decreasing thickness to form an incipient ribbon.

In order to avoid warping of the ribbon longitudinally as well as transversely during its formation as it moves in and along the drawing shaft, it is necessary that the temperature of each face thereof be substantially uniform at all points in each respective line extending transversely of the sheet, and that the temperature of each face of the sheet along corresponding or directly opposite lines, be the same. Also the temperature gradient between successive transverse lines should be gradual and even.

The various prior art means devised for obviating defective sheet glass either are not effective or have disadvantages which render them commercially impracticable.

In one such means there are provided metal screens called "pads," of appropriate dimensions and disposed at judiciously selected locations, in order to cool the ribbon during drawing. This arrangement, while it enables the attenuation or reduction to a certain extent, of the aforesaid undesired heterogeneity of temperature, nevertheless has disadvantages. The emplacement of these screens must be effected manually after opening of access doors in the walls of the drawing apparatus. Since the interior of the drawing shaft is at a pressure below atmospheric, opening of such doors creates a rush of cooler air into the shaft and creates undesired and undesirable temperature variations therein. Furthermore, in the course of time, these screens or pads become encrusted or coated with oxidations, deposits of dust, sulfates, etc., which create variations in rates of heat exchange between the screens and the glass. In addition the action of the screens is not uniform or continuous over the areas of the glass to be cooled, and their utilization is not sufficiently flexible to effect precise and continuous control of thickness because in order to change or modify their action it is necessary to change them or to vary their locations or positions of adjustment.

In another prior art device it has been proposed to provide auxiliary cooling means which are mobile and can thus be moved about from place to place within the apparatus, to correspondingly vary the geometrical relations of the several cooling means and their heat exchange rates with the glass. But the introduction of such mobile auxiliary cooling means into the drawing apparatus, in turn, presents disadvantages because these means perturb and alter the paths of gaseous currents within the apparatus and thus unavoidably act, to themselves create inequalities in temperature at various locations therewithin.

In still another proposed prior art arrangement, cooled or heated gas, in particular derived from burners disposed within the drawing apparatus, is discharged and directed to form gaseous currents moving in desired appropriate paths. Such

arrangements have the drawbacks that the paths of the currents created within the apparatus are not precisely controllable. Furthermore, control of these currents is a delicate operation requiring great skill, so that constant and continuous proper regulation thereof is practically impossible.

The employment of heat radiators has been suggested. But this procedure is directly contrary to the desired aim, which is to cool the glass, not to heat it, and requires the use of devices at a temperature higher than that of the glass. Such devices are expensive and their use involves a large and costly expenditure of energy.

The present invention has for its chief object the provision of an improved method and apparatus for the fabrication of sheets of thermoplastic materials, especially glass, by drawing means which eliminate drawbacks of prior art procedures and apparatuses, and enable precise and accurate regulation and control of the cooling of the material with the resulting production of a ribbon of uniform desired thickness, of excellent quality, and devoid of defects.

In accordance with the foregoing chief object it is a further object to effect the desired heat exchange by radiation between the glass and the cooling means.

Ancillary to the foregoing objects, it is another object to provide an apparatus which assures that every point of each respective line lying in the surface of the ribbon and normal to its direction of travel, will be at the same temperature, that the temperatures of each pair of lines of respective surfaces of the ribbon and located horizontally opposite one another, will be at the same temperature, and that the temperature gradient between successive or contiguous lines will be gradual and smooth.

Yet another object is to provide an apparatus as aforesaid, by which changes in temperatures to effect the desired uniformity, may be manually or automatically controlled in a relatively simple and effective way.

A still further object is to provide a method and apparatus for the production of sheet material, particularly glass, which by reason of the superior product produced, of uniform thickness, reduces losses and costs per unit length of material.

Other objects and advantages of the invention will become clear to those skilled in the art, after a study of the following detailed disclosure.

I have found that the rate of heat exchange between the surface of a standard cooling means and the glass, remains practically constant when the surface temperature of the means remains less than about 0.3 that of the glass subject to the cooling action thereof.

On the other hand, when the temperature of the surface of the cooler is greater than 0.3 that of the glass, the rate of heat exchange varies rapidly with changes in the ratio. These variations become increasingly important as the temperature of the cooling means approaches that of the glass. Of course, the absolute value of heat exchange per unit area decreases as the temperature of the surface of the cooler approaches that of the glass.

According to one feature of the invention there is disposed in proximity to the glass, parallel with its surface, a plurality of surface elements located in side-by-side relation and positioned transversely to the direction in which the glass is drawn. These elements are able to effect heat exchange with the glass by radiation so that it is thus possible to control the cooling or rate of heat exchange at each location along the surface of the incipient sheet, by individually and independently controlling the temperature of each of these elements.

In accordance with an important feature of the invention, the surface temperature of each of the aforesaid elements is kept at a value such that the ratio is greater than 0.3 that of the surface of the glass at the area of exchange.

In a first embodiment for carrying out the inventive method, the cooling means comprises individual juxtaposed elements. In a second embodiment the cooling means comprises a common cover with areas or spots along the length thereof which may be individually kept, each at a selected temperature dif-

ferent from the others, in order to enable a desired rate of heat exchange at each area. Since there is an exchange of heat by conduction along the wall or cover from one area to the next adjacent areas, deleterious effects on the cooling of the glass otherwise caused by abrupt variations in temperature between any one area and the next contiguous areas, are avoided.

The cooling elements may be tubes disposed one after the other through each of which there is impelled a coolant having a sufficiently high boiling point. Such coolants should have a high thermal capacity and, in particular, may be one of the organic substantially nonflammable liquids presently used in industry for heat exchange purposes. It is also possible to use gas, in particular, air.

In another embodiment the cooling elements are so formed that there is a temperature gradient between the external and internal wall surfaces thereof. A coolant having a relatively low boiling point, such as water, for example, may be used. For this purpose the cooling element, at least that portion thereof adjacent the glass, is of a material having a relatively low heat conductivity, such as various cements or plastic material which maintains sufficient strength and solidity at temperatures around 350° C. One such material is known by the trade name of "Teflon." The thickness of the wall formed by the material selected is so chosen that the desired temperature gradient will be established and maintained. The cooling element may also be made of metal forming double walls which form between them a dead air space to effect the desired reduced rate of heat transmission. Or the space between the walls may be filled with a material such as powder of relatively low heat conductivity.

In one construction of the cooling element, a series of tubes are juxtaposed in parallel relation and spaced in the direction transversely of the direction of drawing of the glass. These tubes are cooled upon the side opposite to that facing the glass, by a chilled fluid. The dimensions of these tubes, the thickness of their walls, and the material of which they are made, are so selected that when no fluid is circulating through them, the heat exchange by conduction between the two walls, through the partition, results in a temperature of the external wall slightly higher than the desired operating temperature. Thus the temperature of the external walls of the tubes may be regulated with great precision by the circulation of coolant through the interior of the double walls, about the partition. This coolant may, for example, be air having a temperature such that its circulation will, by convection, lower the temperature of the external walls to the desired value.

The drawing shows several nonlimiting examples of apparatuses by which the method may be carried into practice.

In the drawing:

FIG. 1 is a diagram showing a curve of relative heat exchange rates by radiation;

FIG. 2 illustrates schematically in transverse vertical section, a glass-drawing machine of the Pennvernon-type, equipped with means for carrying the inventive method into practice;

FIG. 3 is a longitudinal sectional detail view showing a portion of a cooling tube, the internal arrangement of partitions and means for feeding coolant to, and exhausting the same from, the tube;

FIG. 4 is a section take in a plane identified by line 4-4, FIG. 3;

FIG. 5 is a schematic vertical section transversely of the sheet, showing a modification;

FIG. 6 is a vertical longitudinal section to an enlarged scale, of the heat exchange element used in the modification of FIG. 5, with outer tube omitted for greater clarity of illustration;

FIG. 6a is a transverse section with outer tube present, and taken in a plane identified by line 6a-6a, FIG. 6;

FIG. 7 is a detail plan view looking from below, showing the staggered or offset relation between the effective cooling sections of two contiguous pipes of the construction depicted upon FIG. 6;

FIG. 8 is an elevational view of a third modification of heat exchange element in which there are formed aligned individual heat exchange units in side-by-side transversely aligned relation;

FIG. 9 is a sectional view taken in a plane identified by line 9-9, FIG. 8, looking in the direction of the arrows;

FIG. 10 is a transverse sectional detail view showing still another form which the cooling element may have;

FIG. 11 is an elevational view looking from right to left, FIG. 10;

FIG. 12 is a perspective view showing details of construction of the assembled apparatus; and

FIG. 13 is a schematic view showing a form of apparatus for automatically controlling the flow of coolant through the several discrete cooling chambers.

FIG. 1 shows a curve representing the variations in heat exchange by radiation, between two spaced surfaces at the respective temperatures of t and T . In this curve, abscissas are in terms of the ratios t/T and ordinates $[1-t^4/T^4]$. Inspection of the curve shows that for values of t/T up to about 0.3, the corresponding values of $[1-t^4/T^4]$ change very little. For example, at ratio $t/T=0.3$, the corresponding ordinate value which is unity for $t/T=0$, is still 0.9919. On the other hand, the decrease in ordinate values becomes very rapid with values of t/T above 0.3.

It is clear that for efficient regulation of cooling of the surface of the glass, it is advantageous that the cooling elements be maintained at temperatures which will be greater than 0.3 that of the glass. For instance, when the temperature t of the cooling surface is kept below 0.3 that of the glass, a substantial change in t does not materially alter the rate of heat transmission per unit area, by radiation from glass to cooling surface. On the other hand, when t is maintained at a value such that the ratio is above 0.3, slight changes in t result in correspondingly large changes in rate of heat transmission.

Upon FIG. 2, I have depicted schematically a glass-drawing machine of the so-called Pennvernon-type. However, this is by way of example only; and it will be well understood by those skilled in the art, that the method and apparatus are easily adapted for use with other types of glass-drawing machines such as the Fourcault, Colburn, and others.

In the apparatus shown, the ribbon of glass 1 is drawn vertically from the surface of the bath of molten glass 2. The usual drawing bar or boat 3, submerged in the bath, assists in causing the incipient ribbon to form into a foot 4 which, as the glass moves upwardly, thins into sheet form for passage between pairs of vertically spaced drawing rolls 5 located in tower or shaft 6. As the incipient sheet moves upwardly at 4 from the surface of the bath, it passes between coolers 7, as is well known in the art.

The temperature of the glass at the location where the ribbon is formed, should be uniform from point to point along lines in the surface of the glass normal to the plane of FIG. 2. In the prior art this uniformity is not attainable in practice, so that the temperature of the glass at successive points along any given line, as aforesaid, varies from point to point where the foot 4 gradually contracts in thickness to form ribbon 1. This lack of uniformity of temperature causes a like variation in viscosity of the glass, with the result that the thickness of the drawn sheet or ribbon correspondingly varies from place to place.

In addition to the usual cooling means 7, previously mentioned, I provide auxiliary cooling means which upon FIG. 2 are identified as a pair of tubes 8 each located below and suspended by suitable means from a respective one of conventional coolers 7.

Figs. 3 and 4 show in vertical longitudinal and transverse section and to an enlarged scale, the construction of one of these tubes 8. Each tube which, as shown upon FIG. 2, is located closely adjacent the foot of the incipient ribbon, is divided into lower and upper chambers 10 and 11, by a wall 9 secured in and extending horizontally and diametrically of the tube. Lower chamber 10, in turn, is divided into compart-

ments such as 12, by semicircular partitions 13 fixed at spaced intervals in and along the chamber. Wall 9 is apertured as indicated at 15 so that there is at least one opening for the exhaust of cooling fluid from its compartment. In the model shown there are two of these openings symmetrically located upon opposite sides of a coolant supply pipe 14.

There is one supply pipe 14 for each compartment. Referring more particularly to FIG. 3, each pipe 14 descends vertically from one of the coolers 7, passes in sealed relation through a respective one of a number of holes in the top of conduit 8, and another hole in wall 9, and has its lower end terminating centrally within a respective one of the compartments.

In operation, cooling fluid or gas such as air, is impelled downwardly through each tube 14, enters its respective compartment 12 where heat exchange by radiation takes place between the molten glass 2 and the exterior walls of each compartment 12. The fluid then passes through aperture 15 and is exhausted from upper chamber 11 and recirculated to means whereby it is recooled.

Thus by regulating the amount or rate of flow of coolant to each of the compartments 12, individually as by means of valves not shown, one in each pipe 14, a very close and precise control is afforded, of the temperature of the glass adjacent each location opposite each of the compartments 12. This is clear from inspection of FIGS. 3 and 4; and any undesired and undesirable temperature differences between contiguous areas in the surface of the glass may be corrected and the incipient sheet maintained at the desired uniform temperature gradient in the direction of its length. The distance between successive partitions 13 depends, of course, on the precision of temperature control required or desired. In most installations a distance of two centimeters enables a temperature control sufficient to avoid differences in thickness of the ribbon which are otherwise unavoidably caused by temperature variations of the glass at and adjacent foot 4 of the incipient sheet or ribbon, and result in imperfections in the finished product.

FIGS. 5 through 7 show a second form which the auxiliary cooling means may have. In this construction, referring especially to FIG. 5, ribbon 1, bath of molten glass 2, drawing boat 3, foot 4, and coolers 7, are as previously described in connection with FIG. 2. At 44 there is identified a metal tube which extends horizontally over the surface of the molten glass and at one side of the cooler 7. While in FIG. 5 only one tube 44 is shown, it will be understood that a second and identically constructed auxiliary cooler is allochirally disposed adjacent the right-hand cooler 7, as viewed in this figure.

A group or bundle of small pipes 40 is disposed within tube 44 in spaced parallel relation as shown upon FIG. 6a. Heat insulating material 41 may fill the interstices between pipes 40, within tube 44.

Each pipe 40 includes a U-shaped depending bend whose sides pass downwardly through a respective pair of apertures in the lower wall of tube 44. Thus, referring the FIGS. 6 and 6a, one of these bends is indicated at 40a and from this it is noted that the bight portion of the bend is parallel with and closely adjacent the surface of the molten glass. See also FIG. 5. As is shown by these figures, each tube has but one bend. The bights of all bends lie in a common plane parallel with the surface of the glass, but are offset with about a 50 percent overlap in this plane and in a direction parallel with ribbon 1. The arrangement of bights of the tubes is well shown upon FIG. 7 from which it is seen that these form two rows 42 and 43 closely spaced and parallel with the surface of the molten glass. Each row comprises a series of bights in contiguous end-to-end aligned relation.

Thus by manipulation of valves 46, FIG. 6, one in each pipe, exteriorly of the melting tank 47, the amount or rate of flow of coolant passing through each of the pipes may be varied to effect a precise control of the surfaces of the glass near the foot 4 where it begins to pass upwardly into an incipient ribbon. Each bight of the tubes may have its upper surface covered

with shield of heat insulation such as indicated at 45. This directs the cooling effect downwardly and promotes efficient heat exchange with the molten glass.

FIGS. 8 and 9 show still another form of the auxiliary cooling means and which is integrated with each of the conventional coolers 7, previously mentioned. The casing of cooler 7, shown as rectangular in cross section upon FIG. 9, is provided with inlet supply pipe 7a and outlet 7b. The base of this casing is divided into discrete chambers 16, by partitions 48 uniformly spaced therealong, so that each chamber may be separately and individually supplied with coolant by a respective one of a plurality of inlet pipes 17. As clearly shown, each inlet pipe has a valve 18 located exteriorly of the cooler. Fluid is exhausted from each chamber through a respective one of a plurality of pipes 19. FIG. 9 shows that compartments 16 are positioned in contiguous side-by-side relation to form a row extending completely across the ribbon, at a location closely adjacent the location where it moves upwardly. As in forms of the invention previously described, the coolant may be air; and by manipulation of valves 18 the amount of fluid impelled through each chamber 16 is varied to effect a precise and exact control of temperature at the surfaces of the glass.

The ribbon of glass is thus formed by rapidly lowering its temperature from about 1000° C. adjacent foot 4, to its solidification temperature which, in general, is about 800° C. The conditions of cooling determine the thickness of the sheet produced.

As shown upon FIG. 2, in order to compensate for variations in thickness it is also desirable to regulate the temperature of coolers 7, at least over the lower parts 7a thereof, effective upon zone "a" of the glass. Since the upper part of the coolers act solely to rapidly lower the temperature of the glass to, say, about 500° C., so that the glass is not damaged by passage between the drawing rolls of the machine, it is not essential as a rule, to closely regulate the temperature in this zone, transversely of the sheet. However, it is advantageous to maintain the temperature of the cooler sufficiently high to avoid deposits or encrustations which would otherwise form thereon.

The separation of the lower portion of the cooler into discrete temperature zones may be effected by any of the means previously described. This separation may be effected in a particularly efficient and commercially satisfactory way, by continuous conduits defined by double walls at the base of the cooler, and impelling through each a current of fluid whose temperature can be controlled individually for each conduit. Such control is readily effected by means of pipes 19, each having a valve 20 therein and each leading to a respective one of the chambers. As shown upon FIG. 2, these pipes may be connected with a single heat exchanger 21 and which may also serve as the supply of fluid for the upper portion or chamber of coolers 7.

After the glass has been formed into a ribbon, it moves into the drawing shaft 6 where it is annealed. It is important, at the moment that each increment of length of the ribbon moves into the shaft, that it be of uniform temperature transversely of the sheet and that both surfaces thereof be at the same temperature. If such conditions do not exist, the ribbon tends to warp or distort and this may cause breakage of the glass when it enters between drawing rolls 5.

In order to avoid any such differences of temperature, auxiliary coolers 22 are disposed upon and adjacent respective surfaces of the ribbon at the location where it enters the shaft. These auxiliary coolers may be formed like coolers 8 previously described in connection with FIGS. 3 and 4. However, other embodiments such as those depicted upon FIGS. 10 and 11 may be used with equally satisfactory results.

Referring to the latter figures, each cooler 22 is shown as rectangular in transverse vertical section. The interior thereof is divided into chambers 48, 49 by a vertical partition 23 extending transversely in and along the cooler. Chamber 48 is, in turn, divided by vertical, laterally and uniformly spaced partitions 24, into a number of discrete compartments 25. Each of

these compartments is individually supplied with coolant through a common conduit 26 having branches 27 each leading to a respective one of compartments 25. A control valve 28 is included in each branch 27. The coolers 22 are disposed, one on each side of the ribbon and are so regulated that when the sheet passes into the drawing shaft, the temperature of each increment of length, forming a narrow strip transversely across the sheet, is the same throughout the length of the strip, and both faces of the strip are at the same temperature.

At the location where it enters the drawing chamber or shaft, the glass is at a temperature of about 500° C. In conformity with the invention, auxiliary coolers 22 will thus have a temperature of the order of 150° to 200° C. However, it is desirable that the surface temperature of these coolers be somewhat above the optimum value, say 350° C., in order to prevent the formation of deposits or encrustations upon the surfaces thereof.

After it enters the drawing shaft, the glass is progressively cooled to a temperature at which it may be cut into sections. Regulation of the rate of cooling is important because it determines the annealing and quality of the glass. In conformity with the invention, auxiliary coolers identified at 29, FIG. 2, are located within shaft 6, as shown, in order to regulate the rate of cooling of the ribbon as it passes upwardly therewith, and thus assure proper annealing. Otherwise variations in such rate will occur because of convection currents within the shaft.

FIG. 12 shows a variation of the cooling means, and which is used to assure regulation of temperature of each point of the surface of the glass at the moment of its formation, the location where it enters the drawing shaft, and/or within the shaft. These cooling means comprise a first U-shaped chamber 31 disposed perpendicularly to the surface of the glass, and a second U-shaped chamber 32 fitting within and in contact with the first. The exterior chamber is supplied with a fluid such as air, through a header 33 and pipe 51 having valve 34 therein. The second or interior chamber 32 is supplied with coolant such as water, through a header 35 and branch pipe 52 which may also have a valve therein, not shown. Fluid is withdrawn from chambers 31 and 32 through pipes 53 and 54, respectively. It will be understood that, as in the embodiments previously described, for example in connection with FIGS. 8 and 9, there are a multiplicity of these assemblies 31, 32, in contiguous side-by-side relation and extending transversely across and adjacent the glass. Each group of chambers 31 may be supplied from header 33 and each group 32 from header 35. The entire assembly is supported by a beam 36 supported at its ends and extending horizontally and transversely across the apparatus. FIG. 2 shows that header 33 is supplied with air from a blower 36. Exhaust pipes 53, FIG. 12, connect with a header 55, FIG. 2, by which air is returned to a cooler or heat exchanger, not shown, and thence returned to the blower for recirculation.

Automatic control of the temperature of the several chambers to maintain the uniformity of temperature as previously described, may be effected by an apparatus such as the one shown upon FIG. 13 operating on the principle of X-ray absorption or optical interference. Referring to this figure, 1 represents to a greatly enlarged scale, a portion of a ribbon of glass being drawn upwardly out of the plane of the figure. A track 56 is fixed horizontally, parallel with and extending across ribbon 1. The track mounts, for guided translation along it, an assembly generally identified at 57, comprising means 58 for detecting changes in thickness, from a predetermined desired value, of the ribbon at each location scanned. By means of this apparatus the thickness of the sheet is tested or explored at each location. Testing every few hours is sufficient because in practice, the thickness varies very little from hour to hour. Measurements may be taken every 10 cm., or less if necessary. There are thus provided L/10 electrical indications every few hours, L being the width of the sheet in centimeters.

These indications or measurements of thickness are sequential effective upon a recording transmitter 59 which converts each indication in sequence, into a corresponding proportional value of pneumatic pressure. A pressure-responsive device 60 consists of a closed casing divided into two discrete chambers by a bellows or diaphragm 61. One of these chambers is connected as at 62 with a source of pressure corresponding, to a predetermined scale, with the desired thickness of the glass. The other chamber is connected as by conduit 63, with the aforesaid recording transmitter. Thus, when the instrument detects at variation of thickness of the sheet at any given location, from that desired, the diaphragm or bellows 61 is flexed to close one or the other of two circuits 64 or 65 and which reversely control a servomotor. There is one servomotor for each respective valve such as 18, 20, 28, 34, etc. When the servomotor is energized by deflection of the diaphragm, to operate in one direction, its valve such as 18', is closed to decrease the rate of flow of coolant to the corresponding compartment. When energized to operate in the other direction, by opposite deflection of the diaphragm, its valve is opened to increase the rate of flow of coolant to that chamber.

By means of a commutator device generally identified at 66 and comprising a contact 67 fixed with assembly 57 to move in synchronism with movement of the measuring instrument, the pressure responsive device is connected sequentially with each servomotor. Thus when an excessive thickness is detected at any point or location adjacent the path of the instrument, the resulting pressure differential effective upon diaphragm 61, closes a corresponding to one of the aforesaid circuits which operates the valve such as 18' controlling flow of coolant to the corresponding chamber such as 16, to decrease the rate of flow sufficiently to increase the temperature at that point or location and thus decrease the thickness thereto to normal or desired value. On the other hand, when the thickness measured at a given point is too small, the effect upon the diaphragm device closes the second contact and thus effects rotation of the servomotor to which it is at that time connected, to decrease the rate of flow of coolant to the chamber at that location. Thereby the temperature at that point or location increases and the thickness of the sheet thereto is correspondingly decreased. In the figure, valves 18', inlet pipes 17 and cooling compartments 16 may be the same as depicted upon FIGS. 8 and 9, it being understood that the same type of automatic control as just described, is equally adaptable to the species of FIGS. 3, 4; 5, 6, etc., and also that, as in FIG. 9, the cooling compartments are in a row extending continuously along and adjacent the line of draw, with each segment of commutator bar 68 in registration with and extending over the same distance, parallel with the track 56, as its corresponding compartment 16.

Numerous modifications, substitutions of equivalents, alterations and changes in relative positions and shapes, will readily occur to those skilled in the art, after a study of the foregoing disclosure. Hence the disclosure should be taken in an illustrative rather than a limiting sense.

In the claims the expression "line of draw" has the usual meaning in the art, such as, referring to FIG. 2, a line defined by the intersection of the plane of ribbon 1, with a plane lying in the surface of the bath of molten glass 2.

Having fully disclosed the invention, what I claim and desire to secure by U.S. Letters Patent is:

1. The method of drawing sheet glass in a fixed vertical direction from a molten bath, comprising, establishing a first plurality of fluid chambers in contiguous, side-by-side relation along a first line parallel with the incipient sheet at one side thereof, normal to said direction, and extending completely and without hiatus across the sheet, for direct heat exchange with and adjacent the incipient sheet, supplying cooling fluid for the incipient sheet to each said chamber, and individually controlling the flow of fluid to each said chamber, to thereby maintain constant the surface temperature of the sheet adjacent said first line.

2. The method of claim 1, and maintaining the effective temperature of the cooling fluid at not less than about 0.3 of the temperature, measured on the Centigrade scale, of the glass at the location of heat exchange with said fluid.

3. The method of claim 1, establishing a second plurality of fluid chambers in contiguous side-by-side relation along a second line parallel with said first line and adjacent the incipient sheet at the other side thereof, normal to said direction, and extending completely and without hiatus across the sheet, for direct heat exchange with and adjacent the incipient sheet, supplying cooling fluid for the incipient sheet to each said chamber of said second plurality, and individually controlling the flow of fluid to each said chamber of said second plurality, to maintain constant the surface temperature of the incipient sheet adjacent said second line.

4. The method of drawing sheet glass in a fixed vertical direction from a bath of molten glass, comprising simultaneously flowing cooling fluid into heat exchange contact with a first plurality of discrete surfaces each in direct heat exchange relation with and adjacent the incipient sheet being drawn upwardly from the bath, and extending continuously and without hiatus in a line parallel with the sheet, normal to said direction, entirely across the sheet, and individually and selectively flowing cooling fluid into heat exchange contact with all or selected ones only of said surfaces, to maintain constant the temperature of the sheet adjacent to and along said line.

5. In a process of drawing glass sheet in which the sheet is drawn upwardly from the surface of a bath of molten glass, along a line of draw lying essentially in the surface of the bath, and progressively cooled to solidification, the step which comprises equalizing the temperature of the glass, in a region where the glass is still plastic, by separately and individually cooling discrete areas of the incipient sheet, said areas extending continuously and without hiatus adjacent and along a line in and transversely of the incipient sheet and parallel with, adjacent and essentially coextensive with said line of draw.

6. In apparatus for drawing sheet glass, a melting tank, means operable to draw glass from said tank in a fixed upward direction and to form the same into a ribbon of essentially uniform thickness and width, first cooler means comprising a continuous, uninterrupted first surface extending parallel to and adjacent the line of draw of the ribbon, first partition means connected with said first surface and forming therewith a first multiplicity of closed, discrete, heat exchange compartments extending in side-by-side relation adjacent and along the line of draw and adjacent to the incipient ribbon being drawn upwardly from the tank, said compartments forming a first row parallel with said line of draw and normal to said direction, first conduit means for supplying and exhausting cooling fluid independently to and from each said compartment, for direct heat exchange contact with the corresponding portion of said first surface, and for direct heat exchange with and adjacent the incipient ribbon being drawn upwardly from the bath of molten glass in said tank, and means operable to selectively and independently control the flow of cooling fluid into and from each said compartment of said first multiplicity.

7. The apparatus of claim 6, said first surface lying essentially in a plane parallel with the surface of molten glass in said tank.

8. The apparatus of claim 6, said direction being vertical, second cooler means comprising a continuous, uninterrupted second surface extending parallel to and adjacent the line of draw of the ribbon, and on the side thereof opposite to said first surface, second partition means connected with said second surface and forming therewith a second multiplicity of closed, discrete, heat exchange compartments extending in side-by-side relation along said line of draw, said second multiplicity of compartments conjointly forming a second row parallel with said line of draw and normal to said direction, second conduit means for supplying and exhausting cooling fluid independently to and from each said compartment of said second multiplicity, for direct heat exchange contact with the corresponding portion of said second surface, and means

operable to selectively and independently control the flow of cooling fluid into and from each compartment of said second multiplicity.

9. The apparatus of claim 6, said surface of said first cooler means comprising a main pipe, a wall in said main pipe extending thereacross and longitudinally therealong, to form with the walls of said main pipe, first and second discrete chambers, said first partition means comprising partitions in and spaced along said second chamber, and dividing the same into said first multiplicity of discrete compartments, said wall having a multiplicity of apertures each opening into a respective one of said compartments, said first conduit means comprising a multiplicity of cooling fluid supply pipes each in communication with a respective one of said apertures.

10. The apparatus of claim 9, said main pipe being disposed to extend adjacent, and parallel with the line of draw, the wall portion of said main pipe, forming said second chamber, confronting the surface of the bath of glass in said tank.

11. The apparatus of claim 6, said first cooler means comprising a closed essentially parallelepipedal casing having its longitudinal axis adjacent and parallel with said line of draw, said casing comprising a bottom wall essentially parallel with the surface of molten glass in said tank, and a vertical sidewall parallel with the plane of the ribbon being drawn, an auxiliary partition in said casing generally parallel with and spaced above said bottom wall and dividing the interior of said casing into lower and upper chambers, said first partition means comprising a multiplicity of spaced partitions in said lower chamber and, in conjunction with the corresponding portions of said bottom and vertical sidewalls, dividing said lower chamber into sequential discrete compartments in side-by-side contiguous relation, to define a row parallel with and adjacent said line of draw, said first conduit means comprising a multiplicity of first supply pipes each opening into a respective one of said compartments, a multiplicity of first exhaust pipes each leading from a respective one of said compartments, a second supply pipe and a second exhaust pipe, each opening into said upper chamber, coolant supply means feeding all said supply pipes, and means in said first supply pipes and operable to individually control the rate of flow of coolant to each said compartment, said upper chamber forming the principal cooler for the ribbon being drawn.

12. The apparatus of claim 11, all said first supply and exhaust pipes passing through said upper chamber and opening into said lower chamber through respective apertures in said auxiliary partition.

13. The apparatus of claim 6, said first cooler means comprising a coolant tube extending parallel with the line of draw, a multiplicity of pipes mounted within said tube, in parallel relation therein, each said pipe including a U-shaped bend, the sides of each bend extending through a respective pair of apertures in said tube, to position the bight thereof exteriorly of the tube, all said bights being essentially coplanar in a plane parallel with the surface of the molten glass in said tank, each said bight being longitudinally offset from and in overlapping side-by-side relation with the next adjacent bight, transversely of the ribbon, all said bights conjointly forming a row extending parallel with and adjacent the line of draw, and substantially coextensive with the width of the ribbon, said flow control means comprising a multiplicity of valves, each in a respective one of said pipes.

14. The apparatus of claim 6, said first cooler means comprising a first multiplicity of discrete U-shaped chambers, means mounting said chambers in side-by-side contiguous relation, each in a respective one of a multiplicity of parallel planes normal to the line of draw, to form a row extending parallel with and adjacent said line of draw and essentially coextensive therewith, said first conduit means comprising a first header and a multiplicity of first pipes each connecting said first header with a respective one of said chambers, a multiplicity of valves each in a respective one of said first pipes, and means for exhausting fluid from each chamber of said first multiplicity.

15. The apparatus of claim 14, said first cooler means also comprising a second multiplicity of discrete U-shaped chambers, each of said second chambers fitting between the sides of a respective one of said first chambers, to extend in a second row parallel with, adjacent, and substantially coextensive with the line of draw, a second header, a multiplicity of second

5 pipes each connecting said second header with a respective one of said second multiplicity of chambers, and means for exhausting fluid from each of said second multiplicity of chambers.
